MERCANDISE DISPLAY

Henry F. Goldsmith, Longport, N. J.

Application April 1, 1941, Serial No. 386,320

3 Claims. (Cl. 35—50)

The present invention relates to a certain new and useful merchandising package for counter display and use and more particularly to a novel means for displaying and selling hair nets and the like.

The selling of hair nets and other articles which occupy a comparatively small space when not in use as compared to their appearance when in use has long presented certain problems. If such hair nets are displayed as a collection of crumpled and formless bits of netting, they make a very unattractive display with little or no customer appeal. In addition, when displayed in this fashion, they are continually handled by customers resulting in their being soiled and stretched and, not infrequently, torn and rendered unsalable. Furthermore, when displayed in this fashion, they can be readily pilfered.

One object of the present invention is to provide a merchandising package for counter display and use of such hair nets whereby a hair net can be displayed as it appears in actual use. Another object of the present invention is to provide a counter display package in which a comparatively large number of such hair nets can be displayed in an attractive and effective manner to customers. Still another object of the present invention is to provide a merchandising package which will minimize handling by the customer and which will be more or less pilfer-resistant.

For the purpose of illustrating the invention, there is shown in the accompanying drawing a form thereof which is at present preferred, since the same has been found in practice to give satisfactory and reliable results, although it is to be understood that the various instrumentalities of which the invention consists can be variously arranged and organized and that the invention is not limited to the precise arrangement and organization of the instrumentalities as herein shown and described.

Referring to the accompanying drawing in which like reference characters indicate identical parts throughout:

Figure 1 represents a front view of one embodiment of the present invention as it appears in actual use.

Figure 2 represents a vertical cross-sectional view along the line 2—2 of Figure 1.

Figure 3 represents a front view of the display head constituting a part of the present invention after the hair nets have been removed and showing the openings in said display head.

Figure 4 represents a back view of the embodiment shown in Figure 1 illustrating the method of removal of the hair nets.

In one embodiment of the present invention I provide a display head which is cut out to show, in profile, a woman's head and neck and a portion of a shoulder. Said head 10 may be formed

of cardboard or other relatively inexpensive material which has sufficient body and strength so that it will not bend or fold readily.

I prefer to have said head 10 colored, in natural colors, so that it will be more attractive and appealing. This can be done by lithographing or painting or printing or in any other appropriate manner. I may also provide a series of such heads in each of which the hair and complexion is colored to correspond to different types; as for example, blond, brunette and auburn. It is possible, however, to have such heads printed merely in black and white. While it is possible to print or color both sides of said head 10, I prefer to color only one side which I may designate as the front 11 thereof, while leaving the back 12 thereof uncolored inasmuch as said back 12, as will be hereinafter described, will not be displayed to customers.

Said head 10 may be made natural size or slightly greater than natural size and is provided with a plurality of openings 13 distributed about that portion of the head on which is shown the hair, as indicated particularly in Figure 3.

In arranging said display package for use, I take a plurality of hair nets 14, corresponding to the number of openings 13 in the head 10 and place them in their crumpled positions against the back 12 of the head 10. I then push and pull through each of the openings 13, which may be more or less approximately $\frac{1}{4}$ " in diameter, a portion of one of the hair nets 14. Enough of the hair net is pulled through the opening to make a tuft 15 of approximately one to two inches in diameter on the front side 11 of the head 10. I prefer to employ a plurality of hair nets 14 which are of different shades, as for example black, light brown, dark brown, light blue, gold, green, pink and so on, so that when said hair nets 14 are pulled through the openings 13, a person viewing the head 10 from the front side 11 thereof will see a plurality of different colored tufts 15 arranged over the hair of the head 10. These tufts 15 are so arranged that they will not entirely cover the picturization of the hair 16 itself, so that the appearance of the net relative to the color of hair shown can be noted by the customer.

A single hair net 17 is then stretched over the head 10 as shown in Figures 1 and 2, and tied with the bow 18 about the neck 19 of said head 10. The net 17 will cover the hair portion 16 of the head 10 and also the wads 15 on the front side 11 of the head 10 and will enclose the remainder of the nets 14 on the back side 12 of the head 10.

As shown in Figure 1, this arrangement will permit the customer to see what the hair net looks like as worn, and, at the same time, to note and compare the different shades and colors

in which the hair net is available by observing the different colored wads 15 as they appear against the hair portion 16 through the hair net 17. The outer net 17 may be of a color most suitable to the particular coloring (blond, brunette or auburn) used on the front portion 11.

It can be readily seen, therefore, that the present invention provides a very neat and attractive, and appealing display unit whereby the customer can observe not only the appearance of the net in actual use, but also the different shades in which the net is available. At the same time, the present invention tends to discourage the handling of the nets 14 by the customer since they are more or less enclosed and isolated by the outer hair net 17. In this way the nets 14 are kept neat and fresh as well as unsoiled and undamaged. Furthermore, since it involves a certain amount of manipulation to remove one of the nets 14, any pilfering by customers is discouraged.

When any particular hair net 14 has been selected by a customer, said hair net can be removed readily by the sales person as is shown in Figure 4. That is, the salesperson raises the more or less elastic edge 20 of the outer net 17 away from the back 12 of the head 10 and reaches in to grasp the portion 21 of the desired net 14 which is behind the back 12. The desired net 14 can then readily be drawn out from under the outer net 17 as shown in Figure 4 without disturbing or disarranging the remaining hair nets 14. The edge 20 of the outer net 17 is then released and snaps back into place to enclose the remaining nets 14.

In this manner, the several individual nets 14 can be removed as desired when sold or when offered for closer inspection. As the several hair nets 14 are removed, the corresponding openings 13 become apparent through the outer net 17;—this, however, does not detract in any way from the appearance of the display so that the display may be used unimpaired until the entire stock of nets is exhausted.

As mentioned previously, it is possible to have two or three heads with different coloring, better to set off the appearance of the different shade nets so that the customer can see which particular shade will best suit her coloring. It has been found, however, that even a single display head has a high degree of sales efficiency.

The head 10 can be held erect by merely propping it against a suitable back surface or preferably, it can be provided with a hinged leg 22 attached to the back 12 thereof so that it can stand erect by itself. The leg 22 can be made more or less triangular in shape being attached to the back 12 along one side 23 of said leg 22 so that the leg 21 lies flat against 12 when the display is not used but can be swung outwardly to provide a support as shown in Figure 2.

The present invention may be embodied in other specific forms without departing from the spirit or essential attributes thereof, and it is therefore desired that the present embodiment be considered in all respects as illustrative and not restrictive, reference being had to the appended claims rather than to the foregoing description to indicate the scope of the invention.

The present invention is particularly effective as a means for displaying the different colors or

shades in which the hair-nets are available, since a dozen or more nets can be displayed on a single head to demonstrate the available colors. Formerly it would have been necessary to employ a dozen or more heads to set off the different colors effectively and clearly. Since this large number of heads was impractical, the customer formerly never was able to observe and compare the different colors to good advantage, so that, not infrequently, either the sale was lost or the customer did not purchase the most effective color for her complexion and hair.

Having thus described the invention, what is hereby claimed as new and desired to be secured by Letters Patent, is:

1. A merchandising unit for displaying and vending women's hair-nets comprising a relatively-flat, cut-out more or less inflexible, generally-lifesize woman's silhouette, the front of said silhouette having face, hair and neck picturizations thereon, said silhouette having a plurality of openings therethrough at the hair picturization thereof, a plurality of different-colored hair-nets each disposed in most part in back of said silhouette and each having a portion thereof passing through one of said openings and forming a more or less compact tuft protruding in front of said silhouette beyond said hair picturization, an outer hair-net placed about said silhouette and enclosing said plurality of hair-nets and said hair picturization, said outer hair-net being relatively elastic at its outer edges and thereby forming a more or less closed and tamper-resisting container for displaying said plurality of transfixing hair-nets, and a support hingedly affixed to the rear of said silhouette at the neck portion thereof and below said outer hair-net, whereby said merchandising unit can be displayed in a generally upright position.
2. A merchandising unit for displaying and vending women's hair-nets comprising a relatively-flat, cut-out more or less inflexible woman's silhouette, said silhouette having one or more openings therethrough at the head portion thereof, one or more hair-nets disposed in most part in back of said silhouette and having a portion thereof passing through one of said openings and forming a tuft protruding in front of said silhouette beyond said head portion, and an outer hair-net placed about the head portion of said silhouette and enclosing said one or more hair-nets and said head portion, said outer hair-net being relatively elastic at its outer edges and thereby forming a closed and tamper-resisting container for displaying said one or more hair-nets.
3. A merchandising unit for displaying and vending women's hair-nets comprising a relatively-flat woman's silhouette formed of cardboard or the like, said silhouette having one or more openings therethrough at the head portion thereof, one or more hair-nets disposed in part in back of said silhouette and having a portion thereof passing through one of said openings and forming a tuft protruding in front of said head portion, and an outer hair-net enclosing said one or more hair-nets and said head portion, said outer hair-net forming a more or less closed and tamper-resisting container for displaying said one or more hair-nets.
